UNITED STATES PATENT OFFICE.

JOHN WEBSTER, OF EAST PROVIDENCE, RHODE ISLAND, ASSIGNOR TO TILDEN-THURBER COMPANY, OF PROVIDENCE, RHODE ISLAND, A CORPORATION OF RHODE ISLAND.

DESIGN FOR A CLOTHES-BRUSH.

40,789.

Specification for Design.

Patented July 26, 1910.

Application filed June 1, 1909. Serial No. 499,603. Term of patent 14 years.

To all whom it may concern:

Be it known that I, JOHN WEBSTER, a citizen of the United States, residing at East Providence, in the county of Providence and State of Rhode Island, have invented a new, original, and ornamental Design for Clothes-Brushes, of which the following is a specification, reference being had to the accompanying drawing, forming part thereof, in which—

I claim—

The ornamental design for a clothes brush as shown.

JOHN WEBSTER.
